DISPLAY BIN

Leroy Keyserling, New York, N. Y., assignor to
Jos. S. Cohen & Sons Co., Inc., New York, N. Y.,
a corporation of New York

Application November 28, 1952, Serial No. 22,479

Term of patent 14 years

(Cl. D80—9)

To all whom it may concern:

Be it known that I, Leroy Keyserling, a citizen of the United States and a resident of New York city, county of New York, and State of New York, have invented a new, original, and ornamental Design for a Display Bin, of which the following is a specification, reference being had to the accompanying drawings, forming part thereof.

Figure 1 is a front elevational view of a display bin, showing my new design;

Figure 2 is a side view; and

Figure 3 is a cross-sectional view substantially along the line 3—3 of Figure 1.

I claim:

The ornamental design for a display bin, substantially as shown.

LEROY KEYSERLING.
